UNITED STATES PATENT OFFICE.

ROYCE L. BEERS, OF DETROIT, MICHIGAN, ASSIGNOR, BY MESNE ASSIGNMENTS, TO RILEY STOKER CORPORATION, OF WORCESTER, MASSACHUSETTS, A CORPORATION OF MASSACHUSETTS.

TYUÈRE STRUCTURE.

Application filed January 14, 1921. Serial No. 437,238.

My invention relates to tuyère structures for underfeed furnaces, and has for its general objects to provide tuyère structure of plate-form, simple, easily manufactured, inexpensive and of advantageous form, appropriate for use as center-tuyère structure of a multiple-retort stoker. And to these ends it consists in the features of construction and arrangement hereinafter set forth and claimed.

In the drawing, Fig. 1 is a perspective view of a tuyère-plate for use in a center-tuyère structure between two retorts of a multiple-retort stoker, and showing fragments of the retort-margins; and Fig. 2 is a horizontal section on line 2—2 of Fig. 1, showing several such tuyère-structures assembled.

In general I form the tuyère elements as narrow plates, say from three-fourths of an inch to an inch and a half thick overall, each comprising a body web that will stand at right angles to the retort-axis and that is of the requisite outline to conform to the intended cross sectional contour of the tuyère-assembly, this body web being marginally flanged on one or both faces along its top and side surfaces that are to be exposed as parts of the fire-box floor but an appropriate one of the flanges being provided with openings through the flange to form the tuyères proper, while the base-portion of the body web is left flangeless and is suitably shaped to interfit with the supporting structure of the furnace and to receive the plate-retaining means.

Thus in Figs. 1 and 2 the tuyère-plates 16^a are of face-contour suitable to span between the margins of parallel retorts 11^a—40 11^a, each plate being symmetrical with respect to a center vertical plane, and each having its body web 17^a extended downward to form the base portion 21^a apertured at 22^a to receive the tie-rod 23^a, the top of the plate being shallowly flanged on both sides as at 18^a and its opposite side-edges being flanged as at 19^a, but interruptedly at registering places on opposite sides of the web, to provide the tuyères proper 20^a. In any superficial shape of the tuyère-plate the body web will be deflected as at 17^a along the marginal portion or portions thereof that lie closely adjacent the mouths of the tuyères proper, so as to give the

tuyère openings a deflection longitudinally of the tuyère-plate assembly, as best shown in Fig. 6. So deflecting the tuyère openings to a slight angle, following the direction of fuel feed along the retort as indicated by the arrow in Fig. 2, tends advantageously to prevent clogging of the openings with ashes or clinkers.

It will be observed that my improved structure has great durability, simplicity and freedom from trouble. The exposed top and side surfaces of the assembly are smooth, that is, without projections or eminences to interfere with movement of the fuel, so that the construction is highly favorable to perfect combustion and freedom from adhesion of clinkers. The tuyère arrangement effectively minimizes accumulation of ash in the tuyère-openings, so tending to maintain adequate combustion and to keep all portions of the tuyère-plate structure adequately cooled by due flow of air. The fuel-receptive area of each plate is small compared with the great expanse of metal presented to the cooling air surface below the plate, and, all parts being integral, greatest heat conductivity is attained for carrying heat rapidly away from the fuel-receptive flanged surfaces. And, should intense heat melt away any fuel-receptive surface, no large orifice is left for the fire to fall through, since the web portions themselves are not far apart; and so the creation of holes in the fire-bed and the dumping of live coals into the ash-pit or under the tie-bars for the tuyère-plates, is effectively prevented.

While I have described in detail an embodiment of my invention, it will be understood that specific changes may be made in embodying my invention; without departure from its spirit, within the scope of the appended claims.

I claim:

1. A plate-tuyère element comprising a body web of substantially uniform thickness, and a shallow marginal flange extending laterally from the body web along those sides that are to be exposed as part of the fire box floor, one of said flange portions being interrupted to provide tuyère openings, and said web being angularly deflected from its normal plane in said openings.

2. A plate-tuyère element for interposi-

tion between adjacent margins of spaced apart retort walls of an underfeed furnace, comprising in an integral structure, a body web shaped in side elevation to span the space between said walls and afford a large cooling surface the side and top edges of which, above the walls, will be exposed to the fuel, and shallow marginal flange portions along all the top and side portions of the body web that are above said walls, such flange portions being narrow to afford minimum exposure to the furnace combustion space and being interrupted at the opposite side margins of the element to form with registering interruptions of the flanges of contiguous elements laterally extending tuyères facing the retort chambers through which tuyères air to support fuel combustion and to cool the body web may pass, the central top area of the flanges being uninter-

rupted and presenting a smooth imperforate surface.

3. A plate-tuyère element for interposition between adjacent margins of spaced-apart, parallel retorts comprising, in an integral structure, a body-web shaped in side elevation to span between and rest upon the retort-margins and to extend above and below the plane of such support, and shallow marginal flanges extending laterally from both sides of said web along its peripheral portions that are to be exposed as part of the fire-box floor, both of said flanges being interrupted at registering places on opposite sides of said web, where tuyère-openings are desired, and said web being angularly deflected at such places out of the plane of the central portion of such web. 25 30 35
